Letter Patent No. 2484, Dated Oct. 2, 1866.

Design for a Wheel

The Schedule referred to in this Letter Patent and making part of the same.

To all whom it may concern

Be it known that I, Amos Rank of Saline in the County of Columbiana and State of Ohio, have invented a new Design for a wheel, of which the following is a full, clear and exact description, reference being had to the accompanying drawings making part of this Specification.

Figure 1. is a view of the outside of the wheel.

Figure 2. is a sectional view of the wheel taken through the red line p. p.

Similar letters of reference indicate corresponding parts in the two figures.

The wheel which I have designed is intended to serve as a traction wheel for reaping and mowing machines. — A, represents the circular rim having on its inner surface, and centrally of its width a bead a, representing the felloe of the wheel. — B, represents the centre piece which has half round projections, b, b, arranged diametrically opposite each other. — C, represents the spokes which radiate from the center of the wheel in straight lines as shown in figure 1, and which have their front edges rounded. — These spokes when seen sideways have a serpentine contour, their ends terminating in short curves c, c, as represented in figure 2. — The bead or rib a, is also curved as shown at d, d, where it joins with the spokes as shown in Figure 1.

This wheel with its six serpentine spokes all radiating from each other presents a very beautiful appearance.

Having thus described my new Design, I claim as new and desire to secure by Letter Patent,

The Design for a wheel as represented and described.
